ATTORNEY.

UNITED STATES PATENT OFFICE

1,993,979

FIREARM

Lewis H. Reed, Springfield, Mass.

Application July 19, 1934, Serial No. 735,982

2 Claims. (Cl. 240—6.41)

This invention relates to improvements in firearms and is directed more particularly to the provision of improved firearms which may be accurately and readily used in darkness.

5 The principal objects of the invention are to provide a firearm which has a novel illuminating device associated therewith arranged for focusing so that the light will be directed towards a certain point which is the focal point of the sights 10 and barrel. By reason of the novel construction of this invention, it is possible to aim the firearm by locating a spot of light on an object rather than by means of the usual sighting means commonly employed so that a bullet will be projected 15 towards the spot of light.

A further object of the invention is to provide a firearm of novel construction which may be operated to simultaneously illuminate an object which it is desired to shoot. It is possible because of the novel construction of the device of this invention to aim the firearm accurately and readily by means of the spot of light and without the use of ordinary gunsights and without the necessity of bringing the firearm up to the level 20 of the eyes. Where a light is ordinarily used an object is merely illuminated and it is necessary to aim the firearm but according to this invention the lighting means is so arranged and constructed that light is so projected that when it appears on an object the firearm is aimed at that spot.

Various other novel features and advantages of the invention will appear in the following description taken in connection with the accompanying drawing, wherein:

Fig. 1 is a side elevational view of a revolver partly in section to show certain features of the invention;

Fig. 2 is an enlarged fragmentary view of the forward end of the barrel of the revolver shown in Fig. 1;

Fig. 3 is an inverted plan view of a trigger guard having certain features of the invention associated therewith; and

Fig. 4 is a small-scale diagrammatic view showing the operation of the device of the invention.

Referring now to the drawing more in detail, the invention will be fully described.

While the novel features of the invention are shown and will be described in connection with a revolver, it is to be understood that those features are adapted for broad and various applications and may be used in connection with other types of firearms such as a shot-gun or the like.

55 I have found that there is a certain amount of

lost motion in the trigger action of firearms. That is to say, the first rearward movement of the trigger takes up the slack and the gun is not cocked until the trigger has moved rearwardly a considerable distance. By means of this invention, I take advantage of this lost motion in the trigger to operate an illuminating means which may be focused on a certain object at which it is desired to fire the gun.

In Fig. 1 there is shown a revolver of usual shape having a stock 2 and a forwardly extending barrel 4. The barrel 4 is, of course, cylindrical so that a bullet or the like passes therethrough and front and rear sights 5 and 7 are provided as shown. At 10 is represented a chamber of usual form and a grip 12 is provided which is preferably hollow for a purpose which will presently appear.

A trigger guard 20 is provided on the lower side of the stock and this preferably consists of a loop secured thereto as shown. A trigger 22 is pivoted to the stock of the revolver by means of a pivot such as 24 and this is movable back and forth in the usual way within the trigger guard. It is the first rearward movement of this trigger 20 22 that is taken advantage of for the novel 25 functioning of my invention.

Secured to the outside of the forward end of the barrel 4 is an illuminating device D. This device D may be secured to the barrel in various 30 ways but preferably a split band such as 40 is employed.

The illuminating device D consists of a socket 30 having a reflector 32 associated with the forward end thereof. A bulb 34 is threadedly receivable in the socket so as to be movable axially in the socket for focusing purposes.

The bulb 34 has a contact 36 on its inner end which is engageable with a contact point 35 provided on an insulating washer 37 within the socket. The washer 37 is preferably spring-pressed as shown.

As a special feature of the invention, the socket is adjustable so that its axis is movable relative to that of the barrel of the gun and in order that a spot of light may coincide with a point of convergence of the axis of the barrel and sighting line.

This may be accomplished by providing a spring 50 such as a small strip of spring-like metal 42 on the under side of the barrel which is adapted to urge the inner end of the socket downwardly. An adjusting screw 44 is preferably provided to bear against the under side of the socket and this 55

may be moved up and down to move the socket and bulb.

A source of electrical energy is provided as an essential element of the structure of this invention. A dry cell battery B is preferably provided and this may be carried within the grip 12 hollowed out for this purpose.

An insulated wire 60 is connected to and extends from the contact point 35 in the bulb socket 10 rearwardly to an insulated contact member 62 associated with the trigger guard 20. Another wire 64 connects the battery B to a spring contact member 68.

The member 68 is so disposed on the trigger guard relative to the trigger that when the trigger 22 is first moved rearwardly for the cocking action it depresses the spring member 68 which contacts with contact 62. In this way, the circuit is completed and the bulb 34 is energized.

It may be seen then that the first motion of the trigger which is utilized to operate the illuminating device of this invention. The light may be focused before the gun is fired and since because of the novel construction the focal points of the light, sights and gun barrel are the same as shown in Fig. 4 the bullet will be projected towards the point at which the light is directed.

The bulb is so focused and the socket is so adjusted relative to the barrel that a spot of light is located at a point where the sighting line and axis of the bore of the barrel converge. When the gun is to be fired, the trigger is moved so that the bulb is energized to produce a spot of light. The gun is pointed so that the spot of light is on the object it is desired to shoot at. By reason of the focusing of the bulb and the adjusting of the socket when the spot of light is on the object, the gun is properly aimed at that object. This is to be distinguished from merely illuminating an object and then aiming the gun. By means of this invention, the gun is correctly aimed when the spot of light is on the object to be fired at.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A firearm comprising in combination, a barrel having a bore, a socket pivotally associated with said barrel for tilting movements on an axis

transverse to the axis of said bore of the barrel, a reflector on the forward side of the socket for directing light rays forwardly of the socket and barrel, a bulb adjustable axially of said socket, adjusting means associated with the lower side of said socket for tilting the socket relative to said barrel into adjusted positions, spring means associated with the upper side of the socket urging the inner end of the socket downwardly, and means for simultaneously energizing said bulb and discharging the firearm, all adapted and arranged whereby the bulb may be adjusted relative to the reflector and socket and the socket and reflector may be adjusted relative to the barrel so that the focal point of rays reflected by the reflector may be in substantial coincidence with the axis of the barrel bore and a bullet discharged from said firearm will strike at said point of coincidence.

2. A firearm comprising in combination, a trigger, a barrel having a bore, sights on the upper side of said barrel arranged to provide a sighting line which converges with the axis of the bore of the barrel at a certain point forwardly thereof, a strap around the barrel adjacent its forward end having spaced parts below said barrel, a socket pivoted between said spaced parts of the strap for tilting movements on an axis transverse to the axis of said bore of the barrel, a reflector on the forward side of the socket for directing light rays forwardly of the socket and barrel, a bulb adjustable axially of said socket, adjusting means associated with said strap below said socket for tilting said socket relative to said barrel into adjusted positions, a spring between the barrel and inner end of the socket co-operating with the adjusting means and urging said inner end of the socket downwardly, a source of energy, circuit connections between said bulb and source of energy and switch means in said circuit connections operable by said trigger, all adapted and arranged whereby the bulb may be adjusted relative to the reflector and socket and the socket and reflector may be adjusted relative to the barrel so that the focal point of rays reflected by the reflector may be in substantial coincidence with said certain point of convergence of the axis of the barrel bore and sight line and a bullet discharged from said firearm will strike at said certain point of convergence.
